G. BOISSONNAULT.
TELEPHONE TRANSMITTER.
APPLICATION FILED JULY 22, 1921.

1,401,754.

Patented Dec. 27, 1921.

Inventor
Gaston Boissonnault

By his Attorney
Philip S. McLean.

UNITED STATES PATENT OFFICE.

GASTON BOISSONNAULT, OF HEWLETT, NEW YORK, ASSIGNOR TO G. BOISSONNAULT COMPANY, OF NEW YORK, N. Y., A CORPORATION OF DELAWARE

TELEPHONE-TRANSMITTER.

1,401,754.

Specification of Letters Patent.

Patented Dec. 27, 1921.

Application filed July 22, 1921. Serial No. 486,738.

To all whom it may concern:

Be it known that I, GASTON BOISSONNAULT, a subject of the King of Great Britain, and a resident of Hewlett, Long Island, 5 Queens county, and State of New York, have invented certain new and useful Improvements in Telephone-Transmitters, of which the following is a specification.

The present invention relates to telephone 10 transmitters and particularly transmitters of the type which I employ with my "Dectograph" apparatus.

In apparatus of this character the transmitter is usually hidden in the room where 15 the conversation takes place and the receiving apparatus is located in an adjoining room, for instance.

The acoustic properties of different rooms vary more or less and I have found that be- 20 cause of this fact the reproductions at the receiving end will sometimes be quite unsatisfactory. I have discovered that these difficulties can be overcome by controlling the intensity or volume of the sound waves act- 25 ing on the transmitter. My invention accordingly involves a transmitter of novel construction designed to overcome the difficulties mentioned, and provided with means by which the intensity of the transmitting 30 vibrations may be controlled to suit the acoustics of a particular location.

In the accompanying drawing I have illus- 35 trated one of the practical embodiments of the invention, but wish it understood that the same may be modified in various respects without departure from the true spirit and scope of the invention as herein- 40 after defined and claimed.

Figure 1 in the drawing referred to, is a central sectional view of the device.

Fig. 2 is a front or face view of the same.

Fig. 3 is a face view of the rear member of the transmitter casing.

The casing of the transmitter comprises 45 in the illustration coöperating back and front shell members 5 and 6 secured together at their edges and clamping between them a diaphragm 7 of carbon or the like having contact with a series of balls or pellets 50 8 supported in suitable cavities in the face of a block 9 of carbon or the like, carried by a base 10 secured to but insulated from the back member 5 of the casing. In this particular disclosure the base 10 has a 55 screw threaded stem 11 extending through

the back of the case and engaged by a nut 12, said base being insulated from the case by insulating disks 13 and an insulating bushing 14.

The transmitter case is provided in the 60 illustration with a forwardly projecting neck 15 for the admission of the sound waves and the sound modifying device is, in this disclosure, directly supported on this neck.

The sound modifying device consists in 65 its present embodiment of a plate 16 having a screw threaded mounting at 17 in the outer end of the neck 15 and a cap or cover 18 having an annular flange 19 overlying the rim of the neck and pivotally connected 70 at its center with the center of the inner plate or disk by a pivot stud 20. The inner plate or disk is constructed with a number of openings 21 therethrough and similarly the outer or cover plate is provided with 75 openings 22 and the openings in the two plates are so formed that they may be brought either wholly or partly into register by turning one plate with respect to the other.

It will thus be seen that by the rotative adjustment of the cover plate over the inner plate, the admission of sound waves to the diaphragm may be governed at will so that if it is found the vibrations of the dia- 85 phragm are too heavy for good voice transmission, the parts may be adjusted to graduate the sound waves and hence modify the effect on the diaphragm. If, on account of peculiar characteristics of a room, the 90 transmitted sounds are relatively weak, the cover plate may be adjusted to open all the sound passages so as to gain the full effect of the sound waves.

If desired, the perforations may be ar- 95 ranged at different radial distances from the pivot center 20 and with the perforations of the inner series offset circumferentially with respect to the perforations of the outer series as shown in Fig. 2, so that at 100 different adjustments either the outer or inner series of openings may be used selectively, that is, one series to the exclusion or partial exclusion of the other series, so as to direct the sound waves either to the center 105 of the diaphragm or to a point removed from the center of the diaphragm. In other adjustments, portions of both series of openings may be in use and, of course, when the full effect is desired, all the openings of both 110

series will be in use. These various adjustments make it possible to control the sound waves so as to get the best effect at the receiving end of the apparatus.

5 The construction disclosed has proved very effective for the purposes intended and is, it will be seen, readily applicable to transmitters now in use.

What I claim is:

10 1. The combination with a telephone transmitter provided with a projecting neck, of a perforated plate having screw threaded connection with said neck and an overlying perforated cap pivotally connected with said plate.

15 2. The combination with a telephone transmitter provided with a projecting neck, of a perforated plate having screw threaded connection with said neck and an overlying perforated cap pivotally connected with said plate and provided with an annular flange surrounding the rim of the neck.

20 3. The combination with a telephone transmitter provided with a neck for admis-

sion of sound waves, a perforated plate de- 25 tachably connected with said neck and an overlying perforated cap pivotally secured to said plate and having an annular flange surrounding the neck and providing an external annular finger-hold by which said 30 overlying cap may be rotatably adjusted over the perforated plate.

4. The combination with a telephone transmitter provided with a sound wave opening, of a pair of valve plates supported 35 in superposed relation over said opening and each provided with a series of inner and outer passages offset circumferentially and arranged at different radial distances from a common center, said plates being rotatably 40 adjustable one with respect to the other to bring either the inner or outer series of openings, or both series, into or out of register.

In witness whereof, I have hereunto set 45 my hand this 15th day of February, 1921.

GASTON BOISSONNAULT.
